(57) **CLAIM**

I claim the ornamental design for a template for making a decorative cloth or fabric, as shown and described.

DESCRIPTION

FIG. 1 is a front view of a template for making decorative cloth and fabric, showing my new design, the template including a main body and a disk received in the main body; FIG. 2 is a rear view of the same;

FIG. 3 is a top plan view of the same;

FIG. 4 is a bottom view of the same;

FIG. 5 is a left side view of the same;

FIG. 6 is a right side view of the same;

FIG. 7 is a sectional view of the same taken along lines 7—7 in FIG. 1;

FIG. 8 is a front view of the main body alone;

FIG. 9 is a rear view of the main body;

FIG. 10 is a top plan view of the main body;

FIG. 11 is a bottom view of the main body;

FIG. 12 is a left side view of the main body;

FIG. 13 is a right side view of the main body;

FIG. 14 is a front view of the disk alone;

FIG. 15 is a rear view of the disk;

FIG. 16 is a top plan view of the disk;

FIG. 17 is a bottom view of the disk;

FIG. 18 is a left side view of the disk; and,

FIG. 19 is a right side view of the disk.
